BENDING MACHINE

Thorval Larsen, Joliet, Ill., assignor to Phoenix Manufacturing Company, Joliet, Ill., a corporation of Illinois

Application February 12, 1945, Serial No. 577,520

13 Claims. (Cl. 59—27)

1

The invention relates to bending machines and has reference in particular to an improved machine for cold bending metal rods such as short lengths of headed rods which are bent to form cold shuts.

As a preliminary operation in the manufacture of said cold shuts the metal rods, approximately five inches in length, are headed at one end and the head is perforated, providing a single opening of a diameter large enough to receive the rod. The machine of the invention has been designed for bending these headed rods into a cold shut which is used industrially as a substitute to replace a broken link. The said articles may also be used as a chain hook and for similar purposes.

A primary object of the invention is to provide an improved machine for cold bending metal rods around a forming die to produce successively two substantially right angled bends in a manner which combines a rolling and a bending action on the metal rod.

Another and more specific object is to provide a machine having an improved mode of operation for bending headed metal rods to form cold shuts and wherein the bending is performed so as to accurately maintain an aligned relation between the head and the terminal end of the rod.

Another object is to provide an improved machine for bending headed metal rods to form cold shuts and which will perform the several bending operations successively, which will bend a plurality of such rods at one time, and which machine will be relatively easy to operate and economical to manufacture, requiring relatively few parts of simple construction.

With these and various other objects in view the invention may consist of certain novel features of construction and operation as will be more fully described and particularly pointed out in the specification, drawings and claims appended hereto.

In the drawings which illustrate an embodiment of the invention and wherein like reference characters designate like parts—

Figure 1 is a side elevational view, parts being shown in section, illustrating the improved bending machine of the invention;

Figure 2 is a top plan view of the bending machine as shown in Figure 1;

Figure 3 is a front elevational view;

Figure 4 is an enlarged fragmentary front elevational view showing the forming die in fixed relation on its operating roll and its position with respect to the grooved idle roller;

Figure 5 is an enlarged fragmentary rear ele-

2

vational view showing the bending die in fixed relation on its operating roll and its position with respect to the grooved idle roller;

Figure 6 is a sectional view illustrating the position of the various bending elements of the present machine at the start of the bending operation;

Figure 7 is a sectional view similar to Figure 6 but showing the various bending elements of the present machine in their position for effecting the first bending operation;

Figure 8 is a similar sectional view of the bending elements of the present machine illustrating the position of the parts at the completion of the first bending operation and at the start of the second bending operation;

Figure 9 is a similar sectional view illustrating the position of the bending elements at the completion of the last bending operation;

Figure 10 is an elevational view of a headed rod;

Figure 11 is a perspective view illustrating the manner in which the headed rod is bent to form a cold shut; and

Fig. 12 is also a front elevation showing certain of the parts in different positions from those of Fig. 3.

Referring to the drawings, particularly Figures 1, 2 and 3, the present bending machine is suitably supported by means of a table or the like having a supporting portion 10 and legs 11. The upper surface of the portion 10 is preferably flat throughout its extent, the same having suitably secured thereto by bolts 12 the base plate 13 at the forward end of the table and the base plate 14 at the rear of the table. Spaced side frames 15 and 16 are secured at the respective sides of the base plate 13 by bolts 17. A plurality of shafts are journaled by the spaced side frames 15 and 16, two of said shafts having geared connection with each other, and the third comprising an idle shaft. The geared shafts 18 and 20 are journaled for rotation by the side frames 15 and 16, said shafts being releasably supported on the frame members by the journal bearings 21. In a similar manner the idle shaft 22 is supported by the side frames, the bearings 23 journaling said shaft and which bearings are releasably secured to the frames respectively.

The shafts 18 and 20 are positioned on the front and rear surfaces of the supporting frames, whereas idle shaft 22 is located on top of said frames approximately on a vertical line midway between said operating shafts.

Shaft 18 is provided with gear 24, whereas shaft

20 is provided with gear 25, both being suitably keyed to their respective shafts and rotating therewith. The roll 26 is also suitably keyed to shaft 18 and the diameter of said roll is such that the circumference of the roll coincides with the pitch circle of the gear 24. A similar roll 27 is keyed to shaft 20 and the circumference of the same also coincides with the pitch circle of its respective gear 25, it being understood that gears 24 and 25 are equal in size and therefore both rolls rotate in unison and to an equal extent.

The shaft 22 supports an idler roller 28 which is provided with a plurality of grooves 30, the said roller rotating freely since it is not connected with the operating shafts 18 and 20. The function of the grooves 30 will be presently described in connection with the first bending operation.

Referring to Figures 4, 5 and 6, it will be observed that the periphery of roll 26 is smooth, whereas, roll 27 is provided with a plurality of grooves 31 which extend around said roll for the entire extent of its uninterrupted surface and which are in alignment with grooves 30 on the idle roller 28. The function of said grooves 31 will be explained in connection with the last bending operation performed by the present apparatus.

The roll 26, which may be termed the first operating roll, provides a carrier for the forming die 32, said forming die 32 having a base portion 33 by means of which the die is releasably secured to the roll. It will be observed that a notch is formed in the roll, providing an opening for receiving the base portion 33, the said portion being releasably secured by means of screws 34. The first operating roll also functions as a carrier for the headed rods 35 which are positioned in a slot 36 provided by the roll. Said slot is located in advance of forming die 32, considering the direction of rotation of the roll as counterclockwise for effecting a bending operation. The forming die 32 extends longitudinally of roll 26 for the full length thereof and said die is provided with a rounded front edge 37 and with a rounded rear edge 38. The first bending operation takes place around front edge 37 and the second bending operation is performed around the rear edge 38. It will be observed that the arcuate curvature of edge 37 has a larger radius than that of 38 and accordingly the first bend formed in the headed rod 35 is greater than the second bend formed in said rod.

The second operating roll 27 is cut away in a manner similar to roll 26 and a bending die 40 is fixed to said roll 27 in the cut-away portion, being releasably secured by means of screws 41. The bending die 40 extends longitudinally of its roll 27 for the full length thereof and in order to perform its bending action said die extends outwardly beyond the periphery of its roll, having a projecting pointed end 42.

The end of shaft 20 opposite gear 25, Figure 2, extends some distance beyond side frame 16, said projecting end receiving the lever 43 which is suitably keyed thereto. The link 44 operatively connects the lever 43 with lever 45, lever 45 being suitably keyed to shaft 46 which extends transversely of the base plate 14. Bearings 47 serve to journal shaft 46, said bearings being releasably secured to base plate 14 by bolts 48. Substantially midway of the length of shaft 46 and between bearings 47 the said shaft is provided with an operating lever 50. It will be observed that rocking of this lever will rotate shaft 46 and

4
through levers 45 and 43 similar rotary movement will be imparted to shafts 20 and 18 and to the respective rolls 27 and 26 fixed to said shafts.

Any preferred form of power may be employed 5 for oscillating shaft 46. As illustrated in the present drawings an air cylinder 51 is employed having suitable connections with a source of air under pressure, which, when admitted to the rear end of cylinder 51, will cause outward movement 10 in a forward direction of piston rod 52. By admitting said air under pressure to the front end of the cylinder the piston rod 52 may be returned to its initial position. The forward end of piston rod 52 is bifurcated for receiving the operating lever 50 which is releasably connected thereto by the pivot pin 53. Bracket 54 projects from the rear end of cylinder 51 and said bracket is likewise bifurcated for receiving the projection 55 of the support 56. A pivot pin 57 releasably and pivotally joins the parts so that bodily movement 15 of cylinder 51 is possible. The right angled bracket 58 forms part of the support 56 and functions to back up said support to absorb the rearward thrust from the cylinder 51. Bolts 59 suitably secure the right angled bracket 58 to the base plate 14.

A guard identified by numeral 60 has enclosing 20 relation with the gears 24 and 25. The rolls 26 and 27 as well as the idle roller 28 are covered at least partially by a top cover plate having a front sloping apron 61 and a rear sloping apron 62. The cover plate between said aprons is provided with a flat supporting area 63 having standing side and rear walls 64 and 65, respectively. The flat supporting area, bounded by the side and rear walls, provides an auxiliary supporting surface for a plurality of headed rods 35 which are thus conveniently positioned in front of the operator for feeding to the machine.

25 In advance of a bending operation the headed rods from the auxiliary support 63 are placed in the slots 66 formed in apron 61. The slotted portion of said apron is located directly over the slot 36 when the roll 26 is positioned as shown in Figure 6. The rolls 26 and 27 assume the positions as shown in Figure 6 at the start of a bending operation. The headed rods 35 are thus simultaneously located in the slot 36, with their headed end in down position, and in one of the slots 66 provided in the apron 61, which last mentioned slot functions to align the rod with a groove 30 formed in the idle roller 28, which, as previously explained, is in alignment with a groove 31 in the roll 27. The apparatus is now 30 ready to perform a bending operation on the headed rods 35 to bend them into the form shown in Figure 11.

35 By admitting compressed air or other fluid under pressure to the rear end of the cylinder 51 the piston rod 52 will be moved outwardly in a forward direction, rotating shaft 46, which rotation is transmitted by the connecting links and levers to the operating rolls 26 and 27. 40 Attention is directed to the first operating roll 26 which carries the rods 35 in a fixed relation with respect to the forming die 32. Roll 26 is caused to rotate in a counterclockwise direction, it being understood, of course that roll 27 therefore rotates in a clockwise direction. The initial rotation of roll 26 will bring the ends of the rods 35 which project above the slot 36 into contact with roller 28. Since the function of the slots 66 is to align the rods 35 with the grooves 30 in said idle roller, the projecting end of each

rod will have interfitting relation with one of the grooves 30, as clearly illustrated in Figure 7.

Continued rotation of roll 26 in a counterclockwise direction will produce a bending of rod 35 in a backward direction over the rounded edge 37 of the forming die 32. The roller 28 is free to rotate during this bending operation, the same functioning as the bending instrumentality for effecting the first bend in the rod. Each rod 35 has interfitting relation with a groove 30 on the idle roller and this interfitting relation continues until the rods are brought into association with the grooves 31 provided by the roll 27. The grooves therefore function to maintain the rods in desired alignment and it will be seen that the initial positioning of the rods is maintained until both bending operations are completed.

The second bending operation on the rods 35 is initiated as the rods are presented to grooves 31 in the roll 27. By referring to Figure 8, it will be seen that this action is about to take place. The projecting end 42 of the bending die 40 has just made contact with the terminal end of the rod 35 and continued movement of the rolls 26 and 27 will result in the die 40 bending the terminal end of the rod 35 around the rear edge 38 of the forming die.

At the completion of the bending operation the rotation of the rolls 26 and 27 is terminated. The piston rod 52 will have reached its limit of travel in a forward direction and accordingly the operator releases air from the rear of the cylinder and admits air under pressure at the forward end of the cylinder. This produces rearward travel of the piston rod and the rolls are thus rotated in a reverse direction to return them to their initial position as shown in Figure 6. The rods 35 will be retained by the forming die 32, all the rods having been bent around said die. It therefore becomes necessary to remove the bent rods from the die and for this purpose the invention provides an ejector 68 fixed to the rod 70 suitably supported for reciprocating movement by the bearing members 71 secured to the side frames 15 and 16. The rod 70 is provided with an actuating handle 72 at its right hand end, as shown in Figure 3, and the operator grasps said handle to effect reciprocation of the ejector 68. The ejector 68 is in alignment with the forming die 32 when said die is positioned as shown in Figure 6. The ejector is also provided with a cut-away portion approximating the shape of said forming die in cross section, being somewhat larger than the die, and upon reciprocating movement of rod 70 it will be understood that the ejector is caused to telescope the forming die, thereby positively pushing from the die the bent rods having supporting relation thereon. Movement of the ejector 68 in a direction toward the left, as shown in Figure 3, will have the effect of sweeping the forming die 32 clean of the cold shuts, and the apparatus is thus placed in condition for another operation, which requires the location of headed rods in groove 36, and which are automatically aligned by positioning the upstanding end of each rod in a slot 66 provided for the purpose by the apron 61.

The completed cold shut produced by the bending machine of the invention is shown in Figure 11, the same having a head 75 which is provided with an opening 76. The first bending operation performed by the apparatus produces the large bend 71 having the radius identified by R₁. The shank of the rod is bent over the front edge 37 of the forming die to form this bend as previously explained, and it will be observed that the angle

formed thereby is somewhat less than a right angle. The first operating roll 26 and the idle roller 28 constitute the bending instrumentalities for this first operation. The second bend is identified by numeral 78, the same having a radius R₂. This second bend is somewhat smaller than the first since the same is produced by the rear edge 38 of the forming die. For producing this second bend the first operating roll acts as a carrier for the rods 35 and which are bent over edge 38 by the bending die 40 actuated and carried by the second operating roll 27. The two rolls therefore function in a conjoint manner to produce this second bend in the cold shuts.

The invention is not to be limited to or by details of construction of the particular embodiment thereof illustrated by the drawings, as various other forms of the device will of course be apparent to those skilled in the art without departing from the spirit of the invention or the scope of the claims.

What is claimed is:

1. In a bending machine, in combination, a first operating roll providing a carrier for the articles to be bent, a forming die secured to said roll, means positioned with respect to the first operating roll for initially bending the articles over the forming die, a second operating roll, and a bending die secured thereto for forming a second bend in the articles by further bending them over the forming die.

2. In a bending machine, in combination, a first operating roll providing a carrier for the articles to be bent, a forming die secured to said roll, a second operating roll, means operatively connecting the rolls whereby they rotate uniformly in opposite directions, a roller positioned with respect to the first operating roll for initially bending the articles over the forming die, and a bending die carried by the second operating roll for forming a second bend in the articles by further bending them over the forming die.

3. In a bending machine, in combination, a first operating roll providing a carrier for the articles to be bent, a forming die secured to said roll, means positioned with respect to the first operating roll for initially bending the articles over the forming die, a second operating roll, a bending die secured thereto for forming a second bend in the articles by further bending them over the forming die, and means for stripping the articles from the forming die following the completion of a bending operation.

4. In a bending machine, in combination, a first operating roll providing a carrier for the articles to be bent, a forming die secured to said roll, a second operating roll, means operatively connecting the rolls whereby they rotate uniformly in opposite directions, a roller positioned with respect to the first operating roll for initially bending the articles over the forming die, a bending die carried by the second operating roll for forming a second bend in the articles by further bending them over the forming die, and means for stripping the articles from the forming die following the completion of a bending operation.

5. In a bending machine, in combination, a first operating roll, a forming die releasably fixed to said roll and having a front bending edge and a rear bending edge, said roll providing a slot adjacent the front bending edge of the die for receiving articles to be bent, said slot having a depth whereby said articles are positioned with their outer ends projecting beyond the forming die, a roller positioned with respect to the first

operating roll for initially bending the projecting ends of said articles over the front edge of the forming die, a second operating roll, and a bending die secured thereto for forming a second bend in the articles by further bending the projecting ends thereof over the rear edge of the forming die.

6. In a bending machine, in combination, a first operating roll, a forming die releasably fixed to said roll and having a front bending edge and a rear bending edge, said roll providing a slot adjacent the front bending edge of the die for receiving articles to be bent, said slot having a depth whereby said articles are positioned with their outer ends projecting beyond the forming die, a roller positioned with respect to the first operating roll for initially bending the projecting ends of said articles over the front edge of the forming die, a second operating roll, means operatively connecting the rolls whereby they rotate uniformly in opposite directions, and a bending die secured to the second operating roll for forming a second bend in the articles by further bending the projecting ends thereof over the rear edge of the forming die.

7. In a bending machine, in combination, a first operating roll, a forming die releasably fixed to said roll and having a front bending edge and a rear bending edge, said roll providing a slot adjacent the front bending edge of the die for receiving articles to be bent, said slot having a depth whereby said articles are positioned with their outer ends projecting beyond the forming die, a roller positioned with respect to the first operating roll for initially bending the projecting ends of said articles over the front edge of the forming die, a second operating roll, a bending die secured thereto for forming a second bend in the articles by further bending the projecting ends thereof over the rear edge of the forming die, and means for stripping the articles from the forming die following the completion of a bending operation.

8. In a bending machine, in combination, a first and second operating roll mounted for rotation on substantially parallel axes in associated relation with each other, means operatively connecting the rolls whereby they rotate uniformly in opposite directions, a roller spaced from said operating roll and mounted for free rotation on an axis parallel to said rolls, a forming die secured to said first operating roll, a bending die secured to said second operating roll, and a plurality of grooves formed in the periphery of said roller and said second operating roll respectively, the grooves in the roller having alignment with the grooves in the second operating roll.

9. In a bending machine, in combination, first and second operating rolls journalled for rotation on substantially parallel axes, means operatively connecting the rolls whereby they rotate uniformly and in opposite directions, a forming die fixed to the first operating roll and having a front bending edge and a rear bending edge, said first operating roll providing a slot adjacent the front bending edge of the forming die for receiving articles to be bent and which are supported with their free ends projecting beyond the forming die, a bending die fixed to the second operating rolls to project beyond the periphery of said roll, and a roller journalled for free rotation on an axis parallel to said rolls and positioned in spaced relation with respect to the first operating roll.

10. In a bending machine, in combination, first and second operating rolls having approximately equal diameters, means journalling said rolls for rotation on parallel axes with their peripheries in approximate contact, means operatively connecting the rolls whereby they rotate uniformly and in opposite directions, a forming die fixed to the first operating roll and having a front bending edge and a rear bending edge both located within the periphery of said roll, said roll providing a slot adjacent the front bending edge of the forming die for receiving articles to be bent and which are supported with their free ends projecting beyond the forming die, a bending die fixed to the second operating roll and having an end projecting beyond the periphery of said roll, a roller journalled for free rotation on an axis parallel to said rolls and positioned in spaced relation with respect to the first operating roll, and power means for oscillating said operating rolls, whereby said rolls have rotation during a bending operation from a loading position where said slot in the first operating roll is substantially vertical to a terminal position where the projecting end of the bending die is located adjacent but in spaced relation to the rear bending edge of the forming die.

11. In a bending machine, in combination, a forming die having a front bending edge and a rear bending edge, a carrier for said die comprising a first operating roll having the die fixed thereto for movement in an arcuate path as a result of oscillating movement of the roll, said roll providing a slot adjacent the front edge of the forming die for receiving articles to be bent and having a depth to cause the free end of said articles to project beyond the forming die, a bending element comprising a roller positioned substantially parallel with the axis of said first operating roll and in the path of the projecting ends of said articles, whereby said projecting ends are bent over the front edge of the forming die when said operating roll has movement in its arcuate path, a bending die, a carrier for said bending die comprising a second operating roll having the die fixed thereto with a free end projecting beyond the periphery of the roll, means journalling said first and second operating rolls in associated relation so that said projecting end of the bending die has movement in an arcuate path which intersects the arcuate path of said forming die, whereby said bending die has conjoint action with the forming die to further bend the projecting ends of said articles over the rear edge of the forming die, means operatively connecting said rolls to cause rotation thereof uniformly and in opposite directions, and power means for oscillating said operating rolls to effect movement of the forming and bending dies in their respective arcuate paths.

12. A bending machine as defined by claim 11 additionally including stripping means for stripping the bent articles from the forming die at the completion of a bending operation, and wherein said roller and second operating roll are formed with aligned grooves for maintaining control of said articles during movement thereof from the first bending operation to the second bending operation.

13. In a bending machine, in combination, a first and second operating roll mounted for rotation on substantially parallel axes in associated relation with each other, means operatively connecting the rolls whereby they rotate uniformly

in opposite directions, a roller spaced from said first operating roll and mounted for rotation on an axis parallel with said rolls, a forming die secured to the said first operating roll, said forming die being included within the periphery of the roll and having a front bending edge and a rear bending edge, said first operating roll providing a slot adjacent the front edge of said forming die for receiving articles to be bent so that they project beyond the forming die, a bending die secured to the second operating roll and having a free end projecting beyond the periphery thereof, a plurality of grooves formed in the periphery of said roller and said second operating roll respectively, the grooves in the roller having alignment with the grooves in the second operat-

5
10
ing roll, and a slotted apron having a fixed position over the first operating roll for initially aligning the articles when inserted in the slot in said roll, the slots in said apron having an aligned relation with the grooves.

THORVAL LARSEN.
